UNITED STATES PATENT OFFICE.

CHARLES ERRETT, OF NEW YORK, N. Y., ASSIGNOR TO PUBLIC SERVICE CUP COMPANY,
OF BROOKLYN, NEW YORK, A CORPORATION OF NEW YORK.

PACKAGE.

1,314,134.

Specification of Letters Patent. Patented Aug. 26, 1919.

Application filed March 31, 1916. Serial No. 87,970.

To all whom it may concern:

Be it known that I, CHARLES ERRETT, a subject of the King of Great Britain and Ireland, and a resident of the borough and county of Richmond, city and State of New York, have invented certain new and useful Improvements in Packages, of which the following is a specification.

My improvement relates to packages of merchandise and more particularly to packages of individual aseptic drinking cups and the like and to fixtures whereby such packages may be supported in a position for ready accessibility for use. The object of my invention is to provide an improved package containing a predetermined number of cups or the like and whereby said cups or the like or at least the open ends thereof are at all times protected against contamination and in which provision is made for the individual removal of each cup or the like from the package after the latter has been broken or unsealed. My invention will be fully described hereinafter and the features of novelty will be pointed out in the appended claims.

Reference is to be had to the accompanying drawings which illustrate examples of my improvement and in which Figure 1 is an elevation of a complete package; Fig. 2 is a similar view after the package has been unsealed with parts broken away; Fig. 3 is a plan view of Fig. 2; Fig. 4 is a detail view of a slightly different package with parts broken away; Fig. 4^a is a detail section showing a slight variation; Fig. 5 is an elevation of one form of supporting fixture with an unsealed package of cups in position thereon; Fig. 6 is a plan view thereof; Fig. 7 is a detail view of a portion of the fixture without the package; Fig. 8 is an elevation of another form of fixture showing a package of cups thereon in section and Fig. 9 is a plan view of the latter fixture.

As shown in the drawings the package comprises a predetermined number of cups 10 constructed in any well known way of customary material and stacked or nested together, said cups as is usually the case, tapering toward their bottoms and having

outwardly flaring annular rims 11 at their open ends. These stacks of cups 10 are wrapped in a covering 12 of paraffined or wax paper or other more or less easily torn or ruptured material which may be water and weather proof and in any case comprises a tubular protecting wrapper drawn tightly about the stack of cups. The opposite longitudinal edges of said covering 12 may be pasted or otherwise secured together to form a tubular wrapper in which the stack of cups is contained.

The one end of the stack as shown in Fig. 4^a may be covered with a cap or the like 12^a which extends over the open end of the one terminal cup and to which the wrapping 12 may be secured in any suitable manner as by folding the one end thereof over the end face of said cap and then fastening same in position in any desired way. Or as shown in Figs. 2 and 4 the one end of said covering or wrapping 12 may simply be tucked or folded into the open end of the one terminal cup, while the other end of said covering may be folded in upon the closed end of the other terminal cup to complete the package. This latter end of the wrapper may be secured in its turned or folded-in condition in any suitable manner as by means of a strip of paper or the like 13 pasted or otherwise secured in position and extending diametrically across the end of the package and preferably along the longitudinal surface thereof at diametrically opposite points. In addition to the above the package includes a band 14 of paper or other material which is heavier or more durable than the wrapper or covering 12 and which extends circumferentially about the package and is preferably pasted or otherwise secured thereto throughout its length. In practice I prefer to use for this band 14 a product commonly known as gummed tape and which is usually made of taugh paper or of fabric and in any case is materially stronger than any part of the wrapper 12. The said band 14 is located at an intermediate point of the package and in some cases as shown in Fig. 4 may be combined with a rubber band or other stiffening

100

or tension member 15 or said band itself may be constructed of elastic material. This rubber band, stiffening or tension member 15 may be secured to the band 14 or it may be 5 separately placed about the package beneath the said band and in some cases may be utilized, in addition to its other functions, as a means for securing the band 14 in position. It will also be obvious that 10 the band 14 itself may be constructed of elastic material and simply stretched circumferentially around the package.

In its initial and complete state the wrapper or covering 12 not only maintains the 15 cups or the like 10 in a properly stacked condition against relative movement in an axial direction whereby a package of minimum dimensions and of maximum compactness is formed but said wrapper or covering 12 also 20 fully protects all of the cups against contamination at least at the vital points and thus maintains them in their intended aseptic condition. When it is desired to use a cup the package is broken by tearing the 25 covering 12 away at the closed end of the one terminal cup, and along the one edge of the band 14. In this manner all that portion of the covering 12 which is initially located between the said one edge of said band 14 30 and the closed end of the terminal cup at one end of the package is removed, the band 14 in all cases being stiff enough to prevent unintentional tearing of the covering beyond the one edge thereof and presenting a relatively stiff edge along which the more easily 35 ruptured covering 12 may readily be torn as indicated for instance at 16. This removal of a portion of the covering 12 as described exposes a portion of the upper ends of a 40 number of cups in the stack, it being understood, however, that the band 14 is so located that, after the end portion of the covering 12 has been removed, the rim 11 of the terminal exposed cup 10 is still within the 45 edge of the band 14 along which said covering has been torn. In this condition of the package the upper edge of the band 14 under its own tension may be caused to turn inward slightly this effect being increased in 50 degree if the rubber band 15 or its equivalent is included in the arrangement or if the band 14 itself is made of elastic material. The terminal cup 10 may now be freely moved lengthwise of the package until this 55 movement is resisted by the frictional engagement of the rim 11 of said cup with the inner surface of the wrapper 12 in the neighborhood of the band 14, after which said cup may be completely withdrawn from 60 said package only if a sufficient pull is exerted thereon to overcome this frictional or other resistance. During this removal of the terminal cup, succeeding cups have a tendency to hang to and follow the terminal

cup as the latter is being withdrawn, in 65 which case the rim 11 of the cup next to the end cup being withdrawn, and possibly the corresponding rims of succeeding cups will be held by the band 14 or more specifically by that portion of the wrapping 12 70 which registers with said band whereby any but the terminal cup is prevented from being completely withdrawn from the package. The action of the band 14 is in all cases sufficient to maintain all cups following the end cup against unintentional removal from the package. An individual removal of a single cup is thus assured each time a cup is desired and the remaining cups are held in the package without necessitating any careful manipulation to secure this result and are protected thereby at least at the rims or open ends thereof. In the complete package, the distance between the flanges of the terminal cups at the opposite 85 ends of the stack or nest is preferably approximately equal to the depth of a single cup, so that even the final cup is readily accessible from the open end of the covering when it is desired to remove said final cup. 90 During the withdrawal of a cup the package may simply be held in one hand while the other hand is used to remove said cup or said package may be supported in a position of ready accessibility by suitable fixtures. 95

It will be understood, if the package is simply held in the hand during withdrawal of a cup that the covering, or so much of it as remains after the package has been 100 unsealed, in addition to its other functions serves to protect the cups remaining in the package against contact with the hand of the person removing the terminal cup and thus protects said cups against contamination 105 from this source. When the package is to be held in the hand as above suggested, said package may have the form shown in Fig. 4^a although the other forms illustrated may also be used in this way. If the package is 110 intended to be combined with my improved fixture hereinafter described it is preferable to arrange the said package as illustrated in Figs. 2 and 3. My improved fixtures as shown in the drawings are particularly adapted for this purpose. As illustrated in Figs. 5, 6 and 7 my improved fixture comprises a substantially upright rod or the like 17 which at its one end carries a head 18, the latter being either rigidly or 115 detachably connected with said rod 17 as may be desired. A plurality of arms 19 extend radially and outwardly from said head 18 and are bent downwardly as at 20 to form depending members 21 which in turn have their lower end portions curved upwardly to form recesses 22 and preferably have their upturned ends provided with 120 125

spherical or other enlargements 23. One of said members 21 is preferably continued upwardly beyond the head 18 to form the resilient extension indicated at 24 in which case 5 the upper free end of said member 24 is preferably curved outwardly as shown at 25, whereby the placing of the cups in position on the fixture is facilitated. In the form 10 being described the rod 17 is continued to form a transverse connecting member 17^a which in turn forms an integral part of a clamping member 17^b, the parts being preferably so proportioned as to bring the rod 17 into axial alinement with the clamping member 17^b as shown in Fig. 6. In using 15 this form of my improved fixture the package is combined therewith by placing that end of the package at which the covering 12 is tucked into the open end of the one 20 terminal cup, over the arms 20 and members 21. The package is then moved lengthwise of said members until the end of said package is finally seated in the recesses 22 in 25 which condition the enlargements 23 are in frictional engagement with the outer surface of the package near its lower end while the portion 24 of the extended member 21 30 engages said package at a point substantially in registry with the band 14. In this condition the package is firmly supported on the fixture with the cups in an inverted condition, it being understood that the portion 24 of the extended member 21 maintains said package against any substantial 35 placement in a direction transverse to its axis or in other words adds rigidity thereto. This extension 24 being resilient may be adjusted to frictionally and resiliently engage the stack of cups and thus aids in 40 holding any cups which may tend to follow the terminal cup during withdrawal thereof against removal from the package. In this manner the unity of the package or stack is preserved. The small upturned ends of 45 the other members 21 and their enlargements 23 maintain the stack of cups as a whole against an axial movement while the terminal cup is being withdrawn for use. The bends 20 of the fixture by engaging the 50 inner surface of the lowermost cup 10 also support the package from the interior as will be readily apparent.

The spherical or other enlargements 23 are designed to fit into the spaces between 55 the flanges of adjacent cups and owing to the resiliency of the members 21 will yield as the stack of cups is inserted in position on the fixture and also when the last few cups are withdrawn from the package. In 60 some cases the cups themselves will yield, if the edges thereof are flexible, during a movement beyond said enlargements 23. The combined package and fixture so far described may be supported in proper position

by simply resting the clamping member 17^b 65 upon a surface or as is preferred this member 17^b may be sprung circumferentially about a container 26 such as for instance the usual bottle in which drinking water is generally distributed. In this case the member 17^b is positioned on the container 26 70 preferably so as to be located beneath a projection 27 thereon which projection may simply comprise a series of raised letters which are usually found in containers of 75 the above indicated type or which is formed by the customary slightly concaved shape of such bottles near the bottom thereof. When thus combined with the container 26 the projection 27 will prevent displacement of the 80 clamping member 17^b in an axial direction during the withdrawal of a cup or cups from the package. In the combined condition of the parts the rod 17 projects upwardly above the container 26 preferably in substantial 85 axial alinement with the axis thereof so that the package of cups is supported in a position of ready and convenient accessibility for use when the water is to be withdrawn from the container 26 for drinking or other purposes. 90

The simple clamping member 17^b may be easily combined for instance with a water bottle which in an inverted condition is usually combined with a cooler and may be 95 instantly removed from said bottle when the latter is empty and a new bottle is to be substituted. The fixture with the clamping device also supports the cups in a position in which they are protected against jostling 100 or other unintentional dislocation and against contamination.

As shown in Figs. 8 and 9 the rod 17^c corresponding to the rod 17 is simply bent transversely as indicated at 17^d and connected or formed integral with a plate 28 provided with suitable apertures 29 for the accommodation of screws or the like whereby said plate 28 may be fastened to a wall or other supporting element. This latter form 105 of my fixture differs from the one first described also in that the members 21^a which project from a head 18^a and correspond to the members 21 all extend downwardly to approximately the same point and simply 110 have the lower free ends bent outwardly and radially as indicated at 21^b, said free ends being also preferably provided with spherical or other enlargements 23. The package 115 is placed upon this fixture in the same way as hereinbefore described, and in its final position has its lower edge resting upon and supported by the outwardly bent portions 21^b as shown in Fig. 8. In the preferred construction the members 21^a are further 120 each provided with a transverse bend 21^c at an intermediate point beneath which edge of the unturned or tucked in portion of the

wrapping 12 is adapted to set when the package is combined therewith as clearly illustrated in said Fig. 8. The said bends 21^c in cooperation with the said inturned portion of the wrapping 12 thus hold the package against removal from the fixture during the withdrawal of a cup for use. This latter form of fixture thus also is adapted to support the package in a position of ready accessibility and to firmly hold the same while the cups are individually removed therefrom and at other times. It will be apparent that the head 18^a with its members 21^a may be connected with the rod 17 and clamping member 17^b and that the head 17 with its members 21 may be combined with the rod 17^c and plate 28 if desired.

In its various forms the supporting portions of the fixture are preferably constructed of resilient material and are adjustable to conform to any changes in form or dimensions which may occur in different packages.

My improved package thus provides an efficient and serviceable protection for the cups during storage, shipment and use and at the same time provides a medium whereby an individual removal of each cup as needed is assured. By having the covering 12 drawn tightly about the cups in a circumferential direction the flange of the terminal cup at the exit end of the package in cooperation with said covering seals the package at its open end and thus prevents any foreign matter from reaching the cups within the package which are thus efficiently protected and covered. It will be understood that the band 14 or its equivalent is so located and the package otherwise so arranged and proportioned that every cup, even the final one, is easily accessible after the wrapping or covering has been partially removed, as before stated. At the same time, my improved fixture provides a means whereby the package of cups may be efficiently supported in an operative position and so as to be easily and readily accessible and so as to prevent loss or misplacing of the package. When supported by the fixtures the cups are further located out of the reach of any drippings from the faucet through which the water is withdrawn so that the cups are protected against injury from this cause, and the fixtures themselves are protected against rusting.

Various changes in the specific form shown and described may be made within the scope of the claims without departing from the spirit of my invention.

60 I claim:

1. A package of merchandise comprising a series of nested, flanged cups and a sanitary covering therefor composed of a frangible, flexible material and a band circumfer-

entially attached to said material and surrounding the package whereby the withdrawal of more than one cup at a time is prevented after the package has been opened. 65

2. A package of merchandise comprising a series of nested, flanged cups, a sanitary paper covering therefor and a paper band circumferentially attached to said covering and surrounding the package whereby the withdrawal of more than one cup at a time is prevented after the package has been 70 75 opened.

3. A package comprising a frangible, flexible protecting covering, a stack of cups wrapped in said covering, and a circumferentially extending reinforcement on said 80 85 covering whereby the reinforced portion of the covering material is brought nearer the axis of the package than the unreinforced parts of the covering to arrest a movement of cups following the movement of a terminal cup out of said package.

4. The combination of a stack of flanged cups, a wrapper inclosing said stack and adapted to be torn away and means adapted 90 to restrict the tearing away of the wrapper 95 and to prevent any but a terminal cup from being removed from the wrapper after it has been torn.

5. The combination of a stack of flanged cups, a wrapper inclosing said stack and 95 adapted to be torn away and a band of tougher material extending circumferentially about said wrapper at an intermediate point, said band being arranged to restrict the tearing away of the wrapper and to prevent any but a terminal cup from being removed from the wrapper. 100 105

6. The combination of a stack of flanged cups, a wrapper inclosing said stack and adapted to be torn away, a band extending 105 circumferentially about said wrapper at an intermediate point, said band being arranged to restrict the tearing away of the wrapper and to prevent any but a terminal cup from being removed from the wrapper 110 and means for producing a circumferential tension in the region of said band.

7. The combination of a stack of cups each having an annular rim at the open end thereof, a wrapper inclosing said stack and adapted to be torn away, and means for restricting the tearing away of said wrapper whereby one or more cups are exposed in an inverted condition, said means being arranged to cause said wrapper to frictionally engage the rims of said cups during removal thereof from the wrapper whereby the movement of any cups which may follow a terminal cup is arrested and the latter alone is removed from the wrapper. 115 120 125

8. The combination of a series of nested, flanged cups, a sanitary covering inclosing said series of cups and folded over the closed

end of one terminal cup and tucked into the open end of the other terminal cup and a band circumferentially attached to said material whereby the withdrawal of more than 5 one cup at a time is prevented.

9. The combination of a series of nested, flanged cups, a protecting cap extending over the open end of the one terminal cup, a sanitary covering inclosing said series of

cups and having its one end portion folded 10 over the closed end of the one terminal cup and its other end portion combined with said cap, and a band circumferentially attached to said material whereby the withdrawal of more than one cup at a time is prevented. 15

In testimony whereof I have hereunto set my hand.

CHARLES ERRETT.
